UNITED STATES PATENT OFFICE.

SPENCER OTIS, OF BARRINGTON, AND FRANK S. WICHMAN, OF HIGHLAND PARK, ILLINOIS, ASSIGNEES TO NATIONAL BOILER WASHING COMPANY, OF CHICAGO, ILLINOIS, A CORPORATION OF MAINE.

SINGLE-TANK BOILER WASHING AND FILLING APPARATUS.

Application filed October 19, 1922. Serial No. 595,540.

This invention relates to an apparatus for washing out and filling boilers, and has for one of its objects to provide an apparatus which will yield at two different outlets or 5 boiler connections at the station where a locomotive has its boiler washed out and refilled, hereinafter referred to as "a locomotive stall", and from a single source, water at two different temperatures appropriate, respectively, for washing out the boiler and for 10 filling it.

It has long been the practice to provide means whereby water supplied at a temperature that is unsuitable for a particular use in 15 the boiler, for instance, water which is initially too hot for handling in the washing out of the boiler, will be automatically tempered before it reaches the outlet through which it is supplied to the boiler. Another object 20 of the present invention is to cause this automatic tempering to be responsive to the act of opening the outlet intended for the release of washout water to the boiler, thereby not only limiting the consumption of tempering 25 water to the duration of the washout operation but leaving the tempering elements inactive when water flows through the same pipe to the boiler filling connection for the purpose of refilling the boiler, for which 30 purpose the temperature of the water may not be inappropriate.

Another object of the invention is to provide a system in which two different water delivering connections are supplied through 35 a common source, and the water is tempered to an appropriate degree when released through one of said connections, but is not so tempered when delivered through the other connection. The invention proceeds upon 40 the principle of providing one of the delivery connections, for instance, the washout connection, with a valve that not only serves to open and close such connection but causes the opening and closing of a shutoff, preferably 45 in the form of a valve in a water pipe that is adapted to supply tempering water to the main through which the water flows to both delivery connections.

Still another object of the invention is to 50 provide a system involving the features already alluded to, in which the delivery of tempering water to the supply main is controlled thermostatically as well as by the aforesaid shutoff that is responsive to the opening and

closing of one of the delivery connections, so 55 that supply of tempering water, while selectively controlled according to the use to which the flow over the line is being put, will be limited to not only the time during which it is needed, but to the quantity necessary to 60 bring the used water to the desired temperature. Accordingly, the invention preferably proceeds upon the further principle of introducing into the supply main a thermostat 65 connected to control the tempering water pipe, through a graduating valve separate and distinct from the shutoff which is responsive to the opening of the delivery outlet, and to have this thermostat located beyond the point at which the tempering water is 70 tapped into the main, so that the delivery of tempering water will be commensurate with the temperature of the mixture.

In the accompanying drawing—

Figure 1 shows by perspective view a plant 75 embodying the several features of the invention; and

Figure 2 is a sectional detail view of the valve of the washout connection.

1 represents a blowoff pipe adapted to be 80 connected through a drop 1^a with a locomotive which is to be cleaned out, and 2 represents a separator into which blown off products, comprising sludge, water, and volatiles, such as steam and vapor, are blown, and from 85 which the sludge and water after giving up their volatiles will escape through a drain pipe 3 having a goose-neck 4 of sufficient height to prevent too sudden evacuation of the separator under blowoff pressure, and 90 having a direct outlet valve 5 which may be opened when necessary. Above the separator 2 is a condenser 6, preferably incorporated in the same physical unit with the separator, in accordance with known practice. Condenser 6 is equipped with spray pipe 7 controlled by valve 8 which is responsive to 95 thermostat 9, and said condenser has a discharge pipe 10 delivering to a tank 11 hot water resulting from the condensing operation. 12 represents a water supply main 100 through which water from the tank 11 is forced by pump 13, and 14 represents a steam pipe for delivering live steam to the pump at a rate determined by valve 15, which is 105 of known construction, purchaseable in the open market at a date prior to the present invention, and which is responsive to load on

the water main 12 which is transmitted to the valve through pipe 16. 17 represents an exhaust pipe from the pump 13 which delivers into the condenser 6. 18 represents a boiler filling connection or drop supplied by the water main 12 and adapted to communicate with a locomotive boiler through means of a flexible hose 19. 20 represents a washout connection which is supplied by the same water main 12, and is adapted to deliver water through flexible hose 21 and washout nozzle 22.

As thus far described, the operation of the apparatus follows conventional and known principles, and the parts may be of known construction.

According to the present invention, the washout connection 20 is provided with a valve 23 which, in addition to its usual function of opening and closing the washout connection, is adapted to open and close a pressure pipe 24 which controls a valve 25 in a cold water pipe 26 which communicates at 27 with the water pipe 12^a which feeds the pump 13, so that whenever the valve 23 is opened to supply water for washing the boiler, valve 25 will be opened to release cold water into the hot water main to temper the same, whereas the opening of the filling connection 18 while valve 23 is closed will draw from the same water main, hot water untempered and therefore more appropriate for boiler filling purposes.

In order that the water in the main 12 may not be changed undesirably in temperature, cold water pipe 26 is provided with another element of control, consisting of a valve 28 under control of a thermostat 28^a introduced into the intake pipe 12^a of the pump 13 and responsive to temperature effects in said intake pipe. Thus, the delivery of tempering water is subject to a dual control, one element of which consists of a valve which is responsive to the selection of the washout connection for delivery of water to the locomotive, and the other element of which is responsive to the temperature of the water being delivered to the line.

While any suitable form of valve may be

used for the connection 23, we prefer to use a construction such as shown in Figure 2, according to which the valve plug is provided with a port 23^a for the water to be delivered, and a port 23^b which adapts it to control the escape of air through the pipe 24. Valve 25 may be of any suitable construction, such, for instance, as a diaphragm valve. It will be relieved of pressure by the opening of the valve 23 so that cold water can escape, and it will be restored to its seat to cut off the escape of cold water when pressure again builds up in the pipe 24 as a result of closing of the port 23^b. So long as valve 23 is open, air will be wasting from pipe 24, but in such small measure as to be immaterial from the standpoint of economy.

We claim:

1. In a boiler washing system, a hot water source, a locomotive stall, a washout water outlet and a filling water outlet at said stall, a delivery pipe connecting said hot water source to both said outlets, a washout valve controlling the washout water outlet, a filling valve controlling the filling water outlet, a tempering water pipe communicating with the delivery pipe at a point in advance of the connection of the delivery pipe with said outlets, a shutoff controlling the escape of water from the tempering water pipe to the delivery pipe, a means of communication between the washout valve and said shutoff whereby the shutoff is opened and closed by the opening and closing of the washout valve, a graduating valve controlling the flow of tempering water released by said shutoff, and a thermostat controlling said graduating valve and subjected to temperature of water in the delivery pipe after the water has been tempered.

2. A boiler washing system as described in claim 1, in which the means of communication between the washout valve and the shutoff comprises a pressure pipe controlled by the washout valve, and a pressure actuated element controlling said shutoff.

Signed at Chicago, Illinois this 16th day of October, 1922.

SPENCER OTIS.
FRANK S. WICHMAN.
